CURVED FRONT ARM LATERAL ARM
AWNING CONSTRUCTION

Frederick A. Anton, Topeka, Kans.

Application August 8, 1932, Serial No. 627,854

5 Claims. (Cl. 156—44)

This invention relates to lateral arm awnings of that class involving the use of a horizontal roller for the winding or unwinding of the fabric, and two or more folding arms for underlying the fabric when in open position and for extending, when in folded condition, substantially parallel with and adjacent to the roller on which the fabric is wound. With the modern type of business building, provided with boxes for receiving the folded awnings or with narrow transom bars, it has been a problem to provide a lateral arm awning with but little pitch or slant when spread, to dispose the awning when folded, including the lateral arms, within the box or in a space approximately the width of the transom bar so that the awning shall not detract from the appearance of an ornate building front, and at the same time avoid the possibility of the folded arms failing to start their unfolding movement as the roller is turned to unwind the fabric.

My object is to meet this objectionable feature by so forming the members of the lateral arms that when folded, the outer arm members are placed under bending stress and hence have a tendency at the ends connected to the front or awning pole, to spring outwardly so that immediately the pull of the wound fabric is relaxed by unwinding movement of the roller, the said arms shall start to unfold. I have found that where the conventional type of arms are folded with the desired compactness close to the rolled up fabric, there is a tendency for them to stick or lock and, in consequence, quick and free opening of the awning cannot be depended upon. However, by forming the outer members of the arms so that they are put under stress when folded, the free opening of the awning is made dependable regardless of the compactness of the arms when folded.

Heretofore, with constructions of the character mentioned, it has been impossible, particularly with low pitched lateral arm awnings, to hold the front arm above or substantially back to the same vertical plane as the rear arm. This relationship of the arms is essential for compact folding. Therefore, a further object of the invention is to produce a lateral arm awning construction of such nature that the front can be folded back to substantially the same vertical plane as the rear arm member, and under some conditions may even cross over the rear arm member.

With the general objects named in view, and others as will hereinafter appear, the invention consists in certain novel and useful features of

construction and organization of parts as hereinafter described; and in order that it may be fully understood, reference is to be had to the accompanying drawings, in which:—

Figure 1 is a front view of a lateral arm awning embodying the invention as it will appear in folded condition. 5

Figure 2 is an enlarged partial top plan view of one of the lateral arms and awning in collapsed condition. 10

Figures 3 to 6 inclusive diagrammatically indicate a comparison between the old style awning arms and the awning arms of the invention as regards the space occupied when folded. 15

Figure 7 is a side elevation of an awning construction in open or unfolded position, the front arm having a double upward bend and its upper edge forming an obtuse angle with relation to the upper edge of the inner arm. 20

Figure 8 is a front elevation of the awning arms of Figure 7, as they appear in folded position. 25

Figure 9 is a side elevation of a lateral arm, comprising outer and inner arms, in open or unfolded position, the front arm having a single upward bend and the upper edge of its major portion forming an obtuse angle with relation to the upper edge of the inner arm. 30

Figure 10 is a front elevation of the awning arms of Figure 9, as they appear in folded position. 35

In the said drawings, where like reference characters identify corresponding parts in all of the figures, 1 indicates a suitable hanger bracket secured to a building front in fixed relation to the opening to be shaded, and connected thereto by a hinge pin 2 is the rear arm member 3 of a folding lateral arm. The number of arms varies in accordance with the width of the awning, but two only are shown in the drawings for convenience of illustration and description. 40

The front end of the arm member 3 carries a yoke 4 receiving a similar yoke 5 on the inner end of an outer awning arm member 6, and said yokes are connected together by a pivot pin 7, so that when the arm is in folded or collapsed position, as will hereinafter appear, it shall fit closely to the awning roller and fabric. 45

The outer arm member 6, adjacent its hinge connection to the inner arm member, is formed with an upward bend as at 8 to dispose the outer or straight portion 9 substantially parallel to but above the inner arm member. It is also formed with an inclined or second upwardly bent portion 10, which, when the arm is in folded position, 50

55

abuts the fabric of the awning wound around the horizontal roller 10a. The inclined portion 10 merges into a second straight portion 11 parallel to the portion 9, and the second 11 of the arm is 5 formed with an offset or shoulder 12, and finally terminates in a portion 13 which preferably is in a plane converging with the balance of the arm as shown most clearly in Figure 2, although this relationship is not essential but may be secured 10 by applying bending or bowing stress through contact of the shoulder 12 with the front pole, as will hereinafter appear. The portion 13 is flattened at its end and formed to receive a pivot pin 14 carried by a bracket or clamp 15 secured 15 to the front pole 16.

As usual in lateral arm awning structures, the awning fabric 11a (Figure 7) is rolled on roller 10a, and the front edge of the fabric is secured to the front pole 16. 20 With an awning constructed as described, fabric winding movement of the roller causes the inner arm members 3 to start turning or swinging on their pins 2, the outer members 6 to commence to swing on their intermediate pins 7, and 25 the outer ends of the arms 6 to move on the pins 14 carried by the front pole. Just before the inner members assume their final positions, the front pole commences to contact with the shoulder 12 of the outer arm member. The pressure 30 imposed tends to force the intermediate hinge pins 7 rearwardly and sets up a stress or tension in the outer arm members tending to throw the front pole outwardly or toward open position. As the winding of the fabric is continued the stress 35 is increased until the inclined portions 10 of the front arm members contact with the fabric wound on the roller, at which time it will be found that the axes of the pins 2 are below the roller, and the inner arms 3 are substantially parallel to the roll- 40 er, the intermediate pins 7 having been forced back to substantially the same vertical plane as the pins 2, and the pins 14 connecting the front pole and the front ends of the front arm members are in a vertical plane just forward of the planes 45 of the other two pins. It will be apparent that the front pins may never be pulled back into exactly the same vertical plane as the intermediate pivots inasmuch as if this should occur, it will be found that the awning structure will 50 lock in unfolding, unless stress is applied to the front arm members so that the latter, as the unwinding of the fabric starts, shall first straighten out to place their pivotal connections with the front pole in a vertical plane forwardly 55 of the intermediate pivots, this final stress being applied by contact of the front arm with the roller.

Considering Figures 3 and 4, it will be noted 60 that the former indicates a short arm and the latter a long arm, each having the same or identical angle at their intermediate pivots 17. When these arms are folded as indicated in dotted lines they will respectively occupy different distances A-B. Therefore, a box of height to accommodate arms folding as at B would be larger than necessary and consequently wasteful of material 65 and space, if used for arms folding as at A.

In Figures 5 and 6, awning arms of different 70 lengths embodying the invention are diagrammatically illustrated. With this construction it will be noted that the intermediate pivot angle 18 may be uniform or identical and that the arms when folded will always occupy the same space 75 C-D regardless of length. A standard transom

bar or box may therefore be employed for all awnings.

In addition to the function and mode of operation of the construction shown in Figures 3 to 6 inclusive, it will be apparent that the upward 5 bend adjacent the pivot 18 in Figures 1, 5, 6, 7, 8, 9, and 10, may permit the major portion of the front arm to overlie the upper edge of the rear arm when a very compact folding, measured horizontally, is desired, whereas when the arms 10 are made as shown in Figures 3 and 4, they come into interfering contact so far from their pivot 17 that any substantial degree of overlap of the outer arm over the inner arm is prohibited. It will be further noted that by having the second 15 bend in the outer arm 6 adjacent its outer end, so that the outer end points at substantially right angles to the plane of the pivot interconnecting the arms, it insures that when the arms are folded they will always occupy the same vertical space 20 regardless of their lengths. It will also be noted that the upward bend adjacent the outer end of the outer arm makes it possible for this end of the arm to be slightly sprung past the circumference of the awning roller when the awning is 25 rolled up with sufficient force to accomplish this result.

A careful consideration of Figures 3 to 6 inclusive will also show that if the angle in the vertical plane formed by the inner arm with the 30 outer arm is known or ascertained, by locating the intermediate pivot in a vertical plane bisecting the angle of the arms, or at right angles to the arms if the arms are in line or parallel as shown in Figures 5 and 6, will always insure 35 that when folded they shall maintain the same relationship, regardless of any increase in length.

Referring further to Figures 3 to 6 inclusive, it will be noted that in Figures 3 and 4, the pivot 17 does not bisect the obtuse angle formed between the lateral arms, and it will be further noted that if the angle between the arms remains the same, but the arms are lengthened, a greater clearance between the cloth or fabric and the arms is secured. This is a desirable 45 result, as the longer the arms the greater the fabric spread and consequently the more chance of the fabric dragging on the arms or on the center pivot. This break or obtuse angle between the arms is usually referred to as the "dip" 50 of the arms. This type of construction has been common, but is subject to one great objection, which has never been successfully overcome up to a recent date, and that is that when the arms are folded back, the longer the arms, the greater 55 the vertical space occupied, as at A and B.

As hereinabove mentioned, I have also found that by having the outer and inner arms in longitudinal alignment with the axis of the center pivot substantially at right angles to the axes 60 of the arms as in Figures 5 and 6, parallel or substantially parallel (referring to the longitudinal axes of the arms) folding is secured, the distances C and D remaining equal regardless of the length of the arms. With the axes of the 65 outer and inner arms in longitudinal alignment, however, the construction is not wholly desirable due to the fact that upon increase in the length of the arms, the clearance of the fabric above the arms grows less and less, when it should increase as above pointed out.

By combining the characteristics of the arms described, as shown in Figures 7 to 10 inclusive, an increase in fabric clearance with an increase 75 in arm length is secured, and at the same time

substantially the same vertical space will receive the arms when folded, regardless of their increase in length, other things remaining the same. This object is accomplished by forming 5 the pivot holes in the outer end of the inner arm and the inner end of the outer arm, in such a fashion that the axis of the pivot bolt will substantially bisect the obtuse angle formed between the arms when they are open or spread. 10 This construction will secure an increased fabric clearance for an increase in arm length and the angle may be of any desired degree provided it gives sufficient clearance for the shortest arms and is not so small as to detract from the 15 appearance of the structure when spread. This angle and bisecting pivot will insure that every set of arms will fold back, other things remaining the same, and occupy the same vertical space regardless of their length, except as regards slight 20 irregularities due to play in the bolt openings and the like. A reasonable error, in any event, does not destroy the effectiveness of the construction for the purpose in view.

However, it has been found necessary in practice to raise the outer end of the outer arm in certain installations to insure that the front pole or board shall occupy the proper position with relation to the front roller, and for this reason the front arm in Figures 7 and 8 is provided with 25 the upward bend 8 and inclination 10, as well as the other reasons hereinbefore pointed out, see Figure 1.

From the above description it will be apparent that I have produced a construction having all 30 of the features of advantage set forth as desirable, and it is to be understood, that although I have illustrated and described the preferred 35 construction, I reserve the right to all changes within the spirit and scope of the invention and appended claims.

I claim:—

1. The combination of a support and a lateral arm awning, of a fabric, a roller carried by the support and receiving said fabric, a front pole 40 connected to the free end of the fabric, a plurality of lateral arms connecting said front pole and the support, and maintaining the pole in parallel relation to the roller; each of said lateral arms comprising a front member and a rear member, the rear members being swingingly pivoted to the support, and the front members being swingingly pivoted at their inner ends to the front ends of the rear arms and at their opposite ends being pivotally connected to the front pole, 45 the outer end of said front member having a shoulder adapted for contact with the front pole before the arm is parallel with the pole to apply

bending stress on the arm for insuring that the pivotal connection between the members shall at all times fall in a vertical plane rearward of the pivot between the front member and front pole to avoid locking of the arms in folded position. 5

2. A lateral arm awning assembly comprising a support, pivotally interconnected inner and outer arm members, the inner arm at its inner end being pivotally secured to the support, a 10 roller, fabric wound on said roller, a front pole connected to the free end of the fabric and pivoted to the outer arm; said outer arm having a shoulder which applies bending stress on the arm through contact with the pole before the arm 15 has completed its closing movement and also having a portion for contact with the rolled fabric to intensify the bending stress on the front pole; the two arms being so connected that their 20 interconnecting pivot when the outer arm presses the fabric is immovable due to the divergence of the arcs in which said pivot tends to swing.

3. In a lateral arm structure for lateral arm awnings, the combination of an outer and an inner arm pivotally secured together at one of 25 their respective ends, the outer arm having an upward bend immediately adjacent its pivot with the inner arm so that when folded the lower edge of the major portion of the outer arm shall 30 line in a higher plane than the corresponding edge of the inner arm, said arm also having an upwardly inclined portion at a point between said upward bend and the outer end of the arm, and a second bend in said outer arm to bring its 35 outer end into substantial parallelism with the inner arm.

4. In a lateral arm awning, the combination of a support, an inner arm pivoted to said support with the line of its longitudinal axis extending 40 downwardly and outwardly, and an outer arm pivoted to the free end of the inner arm with the line of its longitudinal axis extending upwardly and outwardly, the axis of the pivotal connection between the arms bisecting the angles 45 formed at the junction of prolongations of the longitudinal axes of the arms.

5. In a lateral arm awning, the combination of a support, an inner arm pivoted to said support with the line of its longitudinal axis extending 50 downwardly and outwardly, and an outer arm pivoted to the free end of the inner arm with the line of its longitudinal axis extending upwardly and outwardly, prolongations of said axial lines meeting in a point to form a pair of obtuse 55 angles, the axis of the pivotal connection between the arms bisecting the said angles.

FREDERICK A. ANTON.
